Attorney

UNITED STATES PATENT OFFICE.

GEORGE GOULD, OF OLNEY, ILLINOIS.

MOP.

Application filed August 24, 1926. Serial No. 131,257.

My invention relates to improvements in mops, for use upon floors, walls or the like. 45

An important object of the invention is to provide a mop of the above mentioned 5 character, having a self-adjusting mop head provided with a plurality of faces, which may be conveniently brought into engagement with the surface to be treated.

A further object of the invention is to 10 provide a mop of the above mentioned character which is simple in construction, strong, durable and convenient in use.

Other objects and advantages of my invention will be apparent during the course 15 of the following description:

In the accompanying drawings, forming a part of this specification, and in which like numerals are employed to designate like parts throughout the same,

20 Figure 1 is a perspective view of the mop embodying my invention,

Figure 2 is a central vertical longitudinal section through the same, and,

25 Figure 3 is a central longitudinal section through the hub of the device.

In the drawings, wherein for the purpose of illustration is shown a preferred embodiment of my invention, the numeral 5 designates a pivoted or rotatable mop head, as 30 a whole, embodying a central rotatable hub 6, having flanges 7. Attached to the ends of the central hub 6, preferably at the flanges 7, are radial arms 8 formed of wire or the like, and these radial arms are bent 35 outwardly forming extensions 9. The arms 8 and extensions 9 are preferably arranged in triangular groups, thus providing a mop head of three faces. This arrangement is preferred although the number of faces 40 may be increased or decreased. There may be four faces or two faces. The arms 8 and their extensions 9 are for carrying triangular sections of felt 10 or other absorbent fibrous material, held upon the extensions

9 by any suitable means. Any other suitable form of fibrous absorbent material may be employed.

The central hub 6 is rotatably supported within a split circular sleeve 11, formed intermediate the ends of shanks 12, the outer ends of which are bent inwardly to provide lips 13. The shanks 12 are arranged upon oppositely arranged flattened faces 14, formed upon a handle 15, and the lips 13 project into notches 16. A sleeve 17 is 55 slidable upon the handle 15, and is adapted to clamp the shanks 12 to the handle, as shown. By moving this sleeve 17 forwardly toward the reduced end of the handle 15, the shanks 12 may be separated from the 60 handle.

It is to be understood that the form of my invention herewith shown and described, is to be taken as a preferred example of the same, and that various changes in the shape, 65 size and arrangement of parts may be resorted to without departing from the spirit of my invention, or the scope of the subjoined claims.

Having thus described my invention, I 65 claim:

1. In a mop of the character described, a central hub, frames having arms attached to the ends of the central hub and extending radially therefrom, fibrous absorbent 70 material carried by said frames, a sleeve rotatably receiving the hub, and a handle carrying the sleeve.

2. In a mop of the character described, a central hub, frames attached to the ends 75 of the central hub and extending radially outwardly beyond the hub for a substantial distance, fibrous absorbent material carried by said frames, a sleeve rotatably receiving the hub, and a handle carrying 80 the sleeve.

In testimony whereof I affix my signature.

GEORGE GOULD.
